UNITED STATES PATENT OFFICE.

LAVINIA H. FOY, OF NEW HAVEN, CONNECTICUT.

IMPROVEMENT IN REVERSIBLE CUFFS.

Specification forming part of Letters Patent No. 137,907, dated April 15, 1873; application filed December 18, 1872.

To all whom it may concern:

Be it known that I, LAVINIA H. FOY, of the city and county of New Haven and State of Connecticut, have invented certain new and useful Improvements in Reversible or other Cuffs; and I do hereby declare that the following is a full, clear, and exact description of the same, reference being had to the accompanying drawing which forms a part of this specification, and in which—

Figure 1 represents a perspective view of my said improved cuff, the same being shown applied to a holding-button upon an extended wristband. Fig. 2 represents a side view of a section of a cuff made in a somewhat different manner, but still embracing my said improvements. Fig. 3 represents a section on the line A, B, Fig. 2; and Figs. 4 and 5 represent side views of other modifications of the cuff.

To enable those skilled in the art to which my invention belongs to make and use the same, I will proceed to describe it in detail.

In the drawing, Fig. 1, the edges *a a* of the reversible or other cuff *A* are made to button together in the usual manner, but upon one side of the cuff a long slit or opening, *b*, is made, through which the holding-button *c* is passed, when the cuff is turned to one side, thus bringing the button to one end of the slot or opening *b*, as fully shown in the drawing.

It will be seen that, owing to the length of the slot *b*, the cuff can be easily buttoned to the wristband shown in dotted lines, Fig. 1, while, when the cuff is turned to the position shown, the button is not liable to slip through the opening, while the cuff is held in the desired position upon the wrist. The cuff is shown as it appears when applied to the left wrist.

When the same cuff is to be reversed, then it must be applied to the right wrist, where it will occupy the same relative position, as shown in Fig. 1. In other words, the cuff, when the slit or opening *b* is made as shown in Fig. 1, must be changed from one wrist to the other when the cuffs are reversed. The same principle of slots may be applied, as shown in Figs. 2, 4, and 5, whereby the same cuff can be worn in both positions upon the same wrist.

In Fig. 2 a single central slot, *b*, is used, the sides of the slot being connected in the center

by a metal or other suitable fastening, *d*. In this case the holding-button *c* rests against the fastening *d* on one side when one end of the cuff is exposed, while, when the cuff is reversed and worn upon the same wrist, the holding-button *c* rests against the other side of the fastening *d*.

In Fig. 4 the same general results are produced, the only difference being that the sides of the slot are fastened in a different manner, a thread being used and applied to give an ornamental appearance, as shown at *e*, while the outer ends of the slot are formed wider than at the center, or wedge-shaped. By this form of slot the button *c* can be easily passed through the wide part *f*, while, when the cuff is turned to bring the button close to the fastening *d*, the sides of the slot clamp the threads by which the button is sewed to the wristband, and thus the cuff is retained securely in place. The wedged-shaped slot may be used when a single slot is used for the holding-button.

In Fig. 5 two slots, *b b*, are shown in the cuff, the slots being formed out of line with each other. In this form of construction the cuff can be worn in both positions upon the same wrist, one slot being used when one end of the cuff is exposed, and vice versa.

It will be understood that the cuff is turned in both cases, so that the inner ends of the slots rest against the button-fastening when adjusted for use.

The cuffs may be made from linen or other suitable cloth, or from paper or other suitable materials, as may be preferred by the manufacturers.

It will be seen that my improved reversible or other cuff is simple in construction, while, at the same time, it can be easily buttoned upon and taken off of the wrist, while, at the same time, the slots or openings render the cuff more yielding and easy of fit when in use.

The ends of the slots *b* may be made rounding where the button rests, similar to a button-hole in a coat.

The practical merits and value of my invention are greatly increased by reason of the fact that my said improvements in cuffs are equally applicable to cuffs which are made not to reverse as well as those that are so made. For instance, a very cheap and yet beautiful not

reversible cuff, having my invention applied thereto, may be made, the upper or front end being of linen, while the other part, which is covered by the dress or coat sleeve, is made of cotton or other cheap material.

Having described my improved reversible or other cuff, what I claim therein as new and of my invention, and desire to secure by Letters Patent, is—

1. A reversible cuff, provided or made with one or more elongated slots or openings, *b*, for the insertion of the button, substantially as and for the purposes set forth.

2. The combination, with a reversible or other cuff, of a wedged-shaped slot, for the insertion of the button, as and for the purposes set forth.

3. The combination, with a reversible cuff,

of a slot, *b*, for the insertion of the button, the edges of which are united in or near the center, substantially as and for the purposes set forth.

4. The combination, with a reversible cuff, of a slot, *b*, for the insertion of the button, the edges of which are united or connected at the center to form two wedged-shaped sections, substantially as shown in Fig. 4 of the accompanying drawing.

5. The combination, with a reversible cuff, of two slots, *b b*, for the insertion of the button, relatively arranged as shown in Fig. 5 of the accompanying drawing.
